OF BRIDGEPORT, CONNECTICUT, A CORPORATION OF CONNECTICUT.

ELECTRICAL ATTACHMENT-PLUG.

No. 845,543.

Specification of Letters Patent.

Patented Feb. 26, 1907.

Application filed January 7, 1907. Serial No. 351,220.

To all whom it may concern:

Be it known that I, GILBERT W. GOODRIDGE, a citizen of the United States of America, and residing at Bridgeport, in the county of Fairfield and State of Connecticut, have invented certain new and useful Improvements in Electrical Attachment-Plugs, of which the following is a specification.

My invention consists of an improvement in the construction of the electrical attachment-plug forming the subject of the Thomas patent, 797,472, dated August 15, 1905; and the main object of my invention is to so construct the cup or head of the plug as to be able to reduce the chambers containing the contacts to the smallest possible size—that is to say, no larger than is necessary to receive cylindrical contact-sockets.

In the accompanying drawings, Figure 1 is a perspective view of the attachment-plug without a cap. Fig. 2 is a vertical section of the plug with the cap alongside in external view. Fig. 3 is a section through the plug on the line 3 3, Fig. 2, but with a cap having a modified form of contact-finger.

As seen in Figs. 2 and 3, A is the cap of porcelain or other insulating material and provided with the usual central opening for the admission of the wires, the bared ends of which are connected to the terminal plates of the connecting-pins B, (B'). In Fig. 2 I have shown these connecting-pins as vertically split pins of common form to enter and hold by lateral friction against the inner walls of the tubular contact-sockets C C', carried by the insulating-cup D. I form on one side of each of these sockets C C' an opening 4, producing a shoulder 5, with which may engage a shoulder on the spring-latch 6, which is combined with the pin B' on the cap in the construction shown in Fig. 3. Thus these sockets C C' are capable of use with either the style of connecting-pin shown in Fig. 2 or that shown in Fig. 3. In this construction, as in the Thomas attachment-plug, before re-

ferred to, there is an insulating-core E below the cup and around this core the usual metallic screw-shell F, forming the ring terminal of the Edison type, held to the under side of the cup D by a screw H, passing through the flange of the shell and screwed into the bottom of the socket C', which is thereby held in place in the cup. The central terminal consists of the head of a long screw G with washer w and passing centrally up through the core E. The upper end of this screw G is threaded and screwed into a plate J in a chamber 7 on the under side of the cup D. This plate J is bent upwardly, as shown in Fig. 2, so as to carry its outer end clear of the flange of the shell F. A screw 8, passing through an opening in the end of the plate J, enters the socket C and holds the latter in place in its chamber in the upper side of the cup. By thus providing the plate J on the under side of the cup D, I am enabled to reduce the size of the chambers for the sockets on the upper side of the cup, and so reduce the liability to accidental short-circuit and also to give a better appearing plug when the cap is off.

I claim as my invention—

The herein-described attachment-plug, comprising a cap carrying connecting-pins with a cup containing chambers on its upper side, contacts for the cap-pins mounted in said chambers and carried by the cup, and a chamber on the under side of the cup containing a plate electrically connected to one of the contacts on the upper side, a separate insulating-core with a ring terminal and a central securing-screw for the core threaded into said plate, substantially as described.

In testimony whereof I have signed my name to this specification in the presence of two subscribing witnesses.

GILBERT W. GOODRIDGE.
